UNITED STATES PATENT OFFICE.

JOHN T. MARSHALL, OF METUCHEN, NEW JERSEY, ASSIGNOR TO GENERAL ELECTRIC COMPANY, A CORPORATION OF NEW YORK.

ELECTRIC FURNACE.

No. 867,519.

Specification of Letters Patent.

Patented Oct. 1, 1907.

Application filed January 26, 1907. Serial No. 354,227.

To all whom it may concern:

Be it known that I, JOHN T. MARSHALL, a citizen of the United States, residing at the borough of Metuchen, county of Middlesex, State of New Jersey, have invented certain new and useful Improvements in Electric Furnaces, of which the following is a specification.

This invention has for its object the rapid and uniform production of the so-called "metallized" filaments for incandescent electric lamps. Such filaments are manufactured by subjecting the usual carbon filament to excessively high temperatures in an electric furnace for a considerable period of time.

The present invention consists of a furnace in which the carbons are thus treated. It is found that the heat must be applied for about one hour or less, after which the filaments are allowed to cool off. The furnace is therefore arranged to permit a plurality of sets of filaments to be treated in succession, the heating devices being moved from one set to the next at the end of about an hour. The heating appliances comprise a carbon tube in which the filaments are inclosed, and a body of graphite or the like in which the tube is embedded to retain and equalize the heat. The ends of the tube are held in metallic sockets which project through the walls of the furnace and are adapted to receive the terminals of the secondary of a transformer. A carriage is arranged to support the transformer in convenient relation to the plurality of tubes, so that the transformer can be moved along from one tube to the next as desired.

In the accompanying drawings, Figure 1 is a front elevation of one end of a furnace embodying my invention; Fig. 2 shows the boat in which the filaments are packed; Fig. 3 is a cross-section of the furnace, partly in elevation; Fig. 4 is a longitudinal section of one of the metal sockets; and Fig. 5 is a cross section of the same on the line 5-5, Fig. 4.

The body 1 of the furnace is a box-like structure of brick or cement, having an open top. In its side walls are a plurality of openings, those in one wall being directly opposite those in the other wall. In each opening is mounted a metal socket 2, which is capable of ready removal, and has double or hollow walls, in order to provide for the circulation of water or other cooling medium. The water may be introduced through a pipe 3 at one side of the socket, and led off by another pipe from the other side, and in order to insure a complete circulation from end to end of the socket, it may be divided by webs 4 into two chambers 5. The webs do not extend quite to the inner end of the socket, so that the two chambers communicate at this point. The water may if desired be conducted from one socket to another, as by the pipe 6, flowing in series through the entire set on one side of the furnace.

In each end of the socket is a tapering recess, the inner one being preferably the larger. This inner recess 7 is for the purpose of receiving the tapering end of a carbon tube 8. If desired, a carbon bushing 9 may be interposed between the tube and the socket. 60

The furnace is filled with a loose powdered material 10 capable of standing a high temperature, such as artificial graphite. The tubes are embedded in this material, as shown.

Along the top of the furnace is laid a track, composed 65 of rails 11, and on this track is mounted a carriage having a floor 12 and truck wheels 13. The latter are flanged to keep them on the rails, and one of the axles 14 is provided with one or more crank handles 15 by means of which it can be rotated to cause the carriage 70 to travel along the track. On the carriage is supported one or more transformers 16, of suitable capacity for the work intended. The leads 17 connected with the primary coils of these transformers are connected with trolley shoes 18 which are spring pressed against the 75 under side of the stationary parallel conductors 19 erected above and parallel with the furnace, and connected with a suitable source of alternating current. The secondary leads 20 of the transformers are connected with two plates or bars 21, preferably of copper, which are secured to tubular terminals 22 having tapered ends adapted to enter the outer recesses 23 in the sockets 2, one terminal being at the front of the furnace and the other at the rear.

Each terminal is supported by an upright lever 24 85 suitably pivoted to the frame of the carriage; as by means of trunnions 25 journaled in eyes at the ends of straps 26 bolted to a cross bar 27 projecting laterally from the carriage. The levers are composed partly of wood 28, or some other non-conducting material, and 90 at their upper ends are swiveled collars 29 through which passes a shaft or rod 30. One or both of these collars is screw-threaded to form a nut meshing with threads 31 on the shaft. Handles 32 enable the operator to rotate the shaft and thus oscillate the levers, 95 whereby the terminals 22 will be forced into the sockets or withdrawn therefrom as the case may be.

Attached to each terminal and in line with its axis and that of the carbon tube 8 is a tubular handle 33 by means of which the operator can apply the terminal to 100 the socket, an operator being stationed on each side of the furnace to manipulate the two terminals.

The operation of the apparatus is as follows: When the carriage has been brought over the desired pair of sockets, the terminals are applied to the outer recesses 105 therein and the hand wheel is turned to force them into close contact. The current flowing through the carbon tube heats it to an intensely high temperature. A graphite boat or trough 34 is filled with the filaments to be treated and is pushed through the 110

tubular handle and terminal into the carbon tube where it is allowed to remain until the filaments have been properly metallized, usually about one hour. The levers are then backed off and the carriage is moved along to the next pair of sockets.

The process may involve the complete destruction of the carbon tube with each run of filaments. The boat full of filaments can be pushed through without waiting for the tube to cool off, which requires several hours, so that it is desirable to design the furnace for a change of tubes only once in a day. When the tubes are to be replaced by fresh ones, the packing is removed from over the first one, and one of the sockets is withdrawn enough to allow the tube to be taken out and a new one put in and the socket shoved in against it. The second tube is then uncovered, the packing removed therefrom being used to cover the first one, and so on.

It will be observed that the electrical connections can be changed from one tube to another in a very short time. The pressure exerted by the one screw makes all the connections tight, the terminals, sockets and tube forming one tight continuous tube through which the material to be metallized may be passed very readily. If desired, gas may be introduced into the tube by means of the connection 35.

What I claim as new and desire to secure by Letters Patent of the United States, is:—

1. An electric furnace comprising a plurality of tubes, 30 a source of alternating current, and movable terminals adapted to be connected successively to the ends of said tubes.
2. An electric furnace comprising a plurality of carbon tubes, a source of alternating current, movable terminals 35 thereof, and means for forcing said terminals into good electrical connection with any one of said tubes.
3. An electric furnace comprising a plurality of carbon tubes, metal sockets for holding the ends of said tubes, and movable terminals adapted to be forced into contact with 40 said sockets.
4. An electric furnace comprising a plurality of carbon tubes, and tubular terminals adapted to be connected with the ends of any one of said tubes.
5. An electric furnace comprising a plurality of carbon 45 tubes, tubular sockets for the ends of said tubes, and tubular terminals adapted to make contact with said sockets.
6. An electric furnace comprising a plurality of carbon tubes, hollow metal sockets for receiving the ends of said tubes, and means for feeding a cooling fluid through said 50 sockets.
7. An electric furnace comprising a plurality of carbon tubes, a carriage adapted to travel transverse to said tubes, and movable terminals supported on said carriage.
8. An electric furnace comprising a plurality of carbon 55 tubes, a carriage adapted to travel transverse to said tubes,

and tubular terminals supported on said carriage in line with the ends of said tubes.

9. An electric furnace comprising a plurality of carbon tubes, a carriage adapted to travel transverse to said tubes, levers pivoted on said carriage, and terminals carried by 60 said levers.

10. An electric furnace comprising a plurality of carbon tubes, a carriage adapted to travel transverse to said tubes, levers pivoted on said carriage, terminals carried by said levers, and means for moving said levers to force said terminals into good electrical connection with the ends of any one of 65 said tubes.

11. An electric furnace comprising a plurality of carbon tubes, a carriage adapted to travel transverse to said tubes, levers pivoted on said carriage terminals carried by said levers, means for moving said levers to force said terminals into good electrical connection with the ends of any one of 70 said tubes, said means consisting of a shaft uniting said levers and having a screw-threaded connection with one or both thereof.

12. An electric furnace comprising a box-like structure, carbon tubes arranged transverse thereto, a carriage movable along the top of said furnace, and terminals carried by 75 said carriage and adapted to make contact with the ends of any one of said tubes.

13. An electric furnace comprising a box-like structure, carbon tubes arranged transverse thereto, removable tubular sockets in the walls of said structure for holding the ends of said tubes, a carriage movable along the top of said structure, tubular terminals carried by said carriage, and means for forcing them into contact with said sockets. 80

14. An electric furnace comprising a box-like structure, carbon tubes transverse thereto, a carriage movable along the top of said structure, a transformer carried on said carriage, and movable secondary terminals therefor adapted to be brought into connection with the ends of any of 85 said tubes.

15. An electric furnace comprising a box-like structure, a filling of loose refractory material, carbon tubes extending across said box below the surface of the filling, metal 90 sockets in the walls of the box for holding the ends of said tubes, a carriage movable along the top of said box, levers pivoted on said carriage and carrying terminals adapted to engage with the sockets, and a transformer on said carriage having its secondary coils connected with said terminals. 95

16. An electric furnace comprising a box-like structure, a filling of loose refractory material, carbon tubes extending across said box below the surface of the filling, metal sockets in the walls of the box for holding the ends of said tubes, a carriage movable along the top of said box, levers pivoted on said carriage and carrying terminals adapted to engage with the sockets, a transformer on said carriage having its secondary coils connected with said terminals, and a screw shaft uniting said levers for simultaneously operating them. 100

In witness whereof, I have hereunto set my hand this 24th day of January, 1907.

JOHN T. MARSHALL.
